UNITED STATES PATENT OFFICE.

WILLIAM E. WINE, OF TOLEDO, OHIO.

CAR BUFFING DEVICE.

1,215,456.

Specification of Letters Patent. Patented Feb. 13, 1917.

Application filed April 3, 1916. Serial No. 88,622.

To all whom it may concern:

Be it known that I, WILLIAM E. WINE, a citizen of the United States, residing at Toledo, in the county of Lucas and the State 5 of Ohio, have invented new and useful Improvements in Car Buffing Devices, of which the following is a specification, reference being had to the accompanying drawings, forming a part hereof.

10 My invention relates to improvements in buffing devices intended for application to the end sills of freight cars for supplementing the buffing action of the draft gears.

With the rapidly increasing size of locomotives and tractive force thereof, and the increased size and lengths of trains to be hauled thereby, it has been found that modern draft gears have not been sufficiently strong or of a capacity to absorb a sufficient 20 amount of the buffing force to protect a car structure.

It has further been observed that a great 25 many cars are at present in service with the center line of the draft gear considerably eccentric to the center line of the center sills, which ultimately take the buffing strains.

Therefore, the object of my invention is to so construct a buffing device that it will 30 coöperate with the draft gear in absorbing additional buffing strains.

A further object of my invention is to have a buffing device that will coöperate with the horn of a coupler in absorbing a 35 great portion of the buffing strains and transmit them in a more direct line through the center sills of the car.

With these and other objects hereinafter 40 explained in view of my invention consists in the construction and combination of elements hereinafter described and claimed.

In the accompanying drawings which 45 illustrate the preferred embodiment of my invention; Figure 1 is a partial plan view and a partial section on line A—A of Fig. 2. Fig. 2 is a front elevation of same. Fig. 3 is a section of the device on line B—B of Fig. 2.

Similar characters designate similar parts 50 throughout the several figures of the drawings.

Referring now to the parts by number; the housing 1 is provided with the chamber 2 located so that when applied to the car it

will be in line with the horn of a coupler. 55 In this chamber 2 is located the buffing block 3, which coöperate with the flat plate springs 4. The buffer block 3 being provided with ends 5 which contact with flanges 6 for attaining it in position within the 60 chamber 2. The buffer block 3 is also provided with a curved rear surface 7, which bears on springs 4 near its central point when the device is in its normal position.

When assembling this device the buffer 65 block 3 is inserted into position shown by dotted lines as 3^a that revolve in position shown by full lines. The springs 4 are then inserted one at a time through the slot 10 in the top of the housing and moved into 70 position until the space between buffer block 3 and shoulders 11 has been completely filled. The rear walls of chamber 2 are provided with openings 12 through which means can be inserted to position the spring 75 plates 4.

The bottom walls 13 of chamber 2 are provided with openings 14 through which means may be inserted for removing the spring plates 4 in case it is desirable to disassemble 80 the device.

The device as shown on the drawings is provided with extended lugs or bosses 8 on the opposite sides thereof for the reception of the ends of truss rods 9, when used with 85 wood underframe cars. However, when used on the steel underframe cars any suitable attaching means can be provided.

It will be understood from this description that although the improvements of this 90 invention are simple, they accomplish in a thoroughly practical manner all the objects sought and that by their employment a great portion of the buffing strains will be diverted from the draft gear, thus relieving the draft 95 gear of much extreme wear and usage. Furthermore, repairs to this device can be much more easily made than to a draft gear and it will also be noted that the only wear produced in the device will be caused through 100 movement in buffing.

It will of course be understood that I do not desire to be limited to the specific construction shown on the drawings as it is obvious that changes in construction and arrangement may be made without departing 105 from the spirit of the invention.

Having thus described my invention, I

aim in the appended claims to cover all modifications which do not involve a departure from its spirit and scope.

What I claim as new and desire to secure by Letters Patent of the United States is:—

1. In a buffing device, the combination of a housing provided with an integral rear wall portion, a leaf spring member, and buffing means communicating with said spring member, said housing also being provided with a contracted opening for the reception of said buffing means, said buffing means being adapted to be inserted through said opening and positioned within the housing, said spring member having a bearing on said buffing means and the rear walls of said housing and positioned to prevent the removal of said buffing means.

2. In a buffing device, the combination of a housing provided with an integral rear wall portion having two oppositely disposed seats, a leaf spring member engaging said seats, and buffing means communicating with said spring member, said housing being also provided with a contracted opening for the reception of said buffing means, said buffing means being adapted to be inserted longitudinally through said opening and revolved horizontally into position within the housing, said spring member being adapted when

in position to prevent the removal of said buffing means.

3. In a buffing device, the combination of a housing provided with an integral rear wall portion having seats thereon, said housing also having a portion of its front wall cut away forming flanges on opposite sides thereof, a leaf spring member comprising a plurality of flat spring plates adapted to engage said seats and a buffing means provided with a rearwardly extending portion of a curved form adapted to engage said spring member, said buffing means being provided with end portions engaging the flanges on said housing, said housing being also provided with an opening for the insertion of said leaf spring plates, said buffing means being adapted to be inserted longitudinally into said housing between said flanges and positioned within the housing with the end portions thereof in engagement with said flanges, said spring member being adapted when in position to prevent the removal of said buffing means.

This specification signed and witnessed this 1st day of April, 1916.

W. E. WINE.
